UNITED STATES PATENT OFFICE.

WILLIAM E. HASELTINE, OF RIPCOP, WISCONSIN.

SPHYGMOMETER.

1,139,519.

Specification of Letters Patent. Patented May 18, 1915.

Application filed January 10, 1912. Serial No. 670,391.

To all whom it may concern:

Be it known that I, WILLIAM E. HASELTINE, a citizen of the United States, and a resident of Ripon, in the county of Fond du Lac and State of Wisconsin, have invented 5 certain new and useful Improvements in Sphygmometers; and I do hereby declare that the following is a full, clear, and exact description thereof, reference being had to the accompanying drawings, and to the letters of reference marked thereon, which form a part of this specification.

This invention relates to an improved apparatus for measuring the blood pressure in 15 an artery of the arm or other part of the body, the apparatus being generally known as a sphygmometer.

The invention consists of the matters hereinafter described and more particularly 20 pointed out in the appended claims.

The general features of the apparatus are well known and consist generally of a manometer, a pressure controlled tourniquet connected by a pressure tube with said manometer, means for inducing an increasing pressure in the manometer and in the pressure tube in order to gradually constrict the part surrounded by the tourniquet, and valve mechanism for shutting off the source 25 of air pressure when the pulse beat has been stopped by reason of the constriction of the artery. A valve is also usually provided for gradually relieving the pressure in the system in order to diminish the force of the 30 constriction produced by the tourniquet so as to determine the pressure at the instant the pulse again appears.

The object of my invention is to provide an apparatus of the kind described, in compact and portable form so as to be conveniently carried in a suitable box or case and of such construction that it may be quickly and easily set up for use and in addition to provide such an apparatus in which the 40 pressure is supplied as wanted without the necessity of operating a pump or other pressure inducing device during the time the blood pressure is being observed.

In the drawings: Figure 1 is a view representing my improved apparatus in side elevation when set up ready for use. Fig. 2 is a view of the apparatus in top plan, the mercury tube being shown in transverse section and the top wall of the air-storage tank 50 being partly broken away to show the interior. Fig. 3 is a view representing a trans-

verse vertical section through Fig. 2 on the line 3—3 thereof. Fig. 4 is a view representing a partial horizontal section through Fig. 1 on the line 4—4 thereof. Fig. 5 is a 60 view representing on an enlarged scale a transverse vertical section through Fig. 2 on the line 5—5 thereof. Fig. 6 is a view representing the left-hand end part of the apparatus, as shown in Fig. 1, in side elevation, on an enlarged scale, the mercury tube being shown in longitudinal central section, and being turned down into the position it occupies when the apparatus is not in use.

Referring now to that embodiment of my 70 invention illustrated in the drawings, 10 indicates a closed tank or reservoir adapted for the storage of air under compression. A pump 11 is provided for charging the 75 tank. Said pump may be of any familiar construction, such, for example, as the familiar "bicycle pump" comprising a cylinder and a piston and having a handle 13 projecting from the cylinder for actuating the piston. As shown herein, said pump is 80 located within the tank and is rigidly secured to the end wall 10^a of the tank through a suitable aperture in which one end of the pump projects so that the handle 13 is located within the tank in position to be 85 grasped by the operator. The walls of the tank are preferably prolonged beyond the end of the pump so as to provide a recess 13^a at the end of the tank within which the 90 handle 13 is located.

The tank or reservoir 10 is preferably made rigid with a base-plate 14 which has a projection 14^a extending laterally from the tank and a projection 14^b which projects beyond one end of the tank. On the end projection 14^b of the base-plate, as shown in the drawings, is secured a manometer comprising a mercury cup 15 and a long glass tube 34 connected at one end with the bottom of the mercury cup and open at 95 its other end. The mercury cup has a base 15^a, which rests upon the base-plate, and contains a cylindric mercury chamber 16 which is located somewhat above the level 100 of the base-plate 14. Said cup is closed by a cap 17 having an internally threaded flange 17^a screwed upon the internally threaded upper end of the cup. Said cap has an upright central boss 18 having a vertical passage 18^a which opens into the mercury cup 16. As shown, said passage 18^a 105 extends through a depending nipple 19

made integral with the lower side of the cap and extending downwardly into the interior of the cup to a point a distance below the lower face of the cap. The boss 18 is provided above the top of the cap with a transverse passage 20, which intersects the vertical passage 18^a. In one end of the passage 20 is secured a tube 21 leading from the interior of the tank 10, and in its other end is secured a tube 22 adapted for connection with a flexible tube 23 which leads to the tourniquet in the usual manner. The upper end of the vertical passage 18^a in the boss 18 is threaded to receive a screw-threaded valve stem 24 having a longitudinally extending V-shaped notch 25, the upper end of which is normally closed by means of a washer 26 interposed between the head 24^a of said valve and the upper end of said boss. A valve 21^a of familiar construction is placed in the tube 21 intermediate the tank 10 and the passage 20 in the boss of the cap and is adapted to control the flow of air from the tank to the manometer and 25 to the tube 20 leading to said tourniquet.

The bottom of the mercury cup is provided with a downwardly extending passage 27 which leads from the interior of the cup to a laterally directed opening 28 in which 30 is secured a conical plug 29. Said plug is provided with a longitudinal central passage 30 which opens at one end through the end of the plug into the passage 27 in the mercury cup and at its other end opens laterally through the conical surface of the plug.

31 indicates a tube having a closed lower end 31^a provided with a transverse conical bore adapted to receive the conical plug 29. Said tube is adapted to rotate on said plug and is retained thereon by means of a collar 32 and a screw 33. Within the tube 31 is supported the glass mercury tube 34, the lower end of which communicates with a passage 35 formed in the closed end of the tube 31 and opening into the transverse bore therein at such a position as to be capable of being brought to register with the laterally directed outlet of the passage 30 in the plug 29, when the tube 31 is rotated on said plug. It is apparent that by rotating the tube 31 with the mercury tube 34 on the plug 29, the communication between the interior of the glass mercury tube 34 and the passage 30 50 may be opened or closed.

37 indicates a scale arranged adjacent to the glass tube 34 and adapted to measure the height of the mercury when it rises in the tube 34. Said scale, as shown, consists 60 of a half-round tube 37^a adapted to receive the glass tube 34, said tube being provided with flat lateral projections 37^b, 37^b, located in the same plane and extending vertically at each side of the tube 34. Said flanges 65 are provided with graduations, indicating

a suitable scale. The upper end of said scale is secured to the mercury tube 34 by means of a U-bolt 37^c. The half-round tube 37^a terminates at and rests upon the upper end of the tube 31, which supports the mercury tube, while the lateral flanges on said tube 37^a are carried down below the top of said tube 31, as clearly shown in Fig. 5. They are there secured between lateral flanges 40^a of a half-round tube 40 which 70 engages against the tube 31, and the flanges 41^a of straps 41, located respectively near the top and the bottom of the tube 31. Said tube 31 is cut away in front of the scale to provide an opening 42 (see Figs. 1 and 6) so 75 that the level of the liquid at the zero point of the scale may be observed.

The operation of the device is as follows: When not in use, the mercury tube 34 of the manometer is turned downwardly by means 80 of the rotative connection with the plug 29 into a horizontal position alongside the tank 10, as shown in Figs. 1 and 2. In order to make this movement without losing the mercury in the tube, the apparatus is first 85 turned so as to swing the mercury cup and tube in the common plane of their vertical axes to the right as viewed in Fig. 5. This movement raises the level of the plug and lowers the relative level of the bottom 90 of the mercury cup so that the mercury in the tube is caused to flow back into the mercury cup. The depending stem 19 on the cap of the mercury cup prevents any mercury from flowing out through the passage 100 in the cap during this movement, even in case the mercury cup is completely inverted, said stem being preferably made long enough so as to project above the level of the mercury when the apparatus is in the 105 latter position. After the mercury has been thus drawn from the glass tube and from the tube 31, the scale and tube may be rotated on the plug 29 thus closing off the passage 30 and locking the mercury within 110 the mercury cup and the plug 29. When the mercury tube is again brought to upright position, communication is opened between the passage 30 and the mercury tube 34 and the mercury rises in the tube until 115 the levels of the mercury in the tube and in the cup are the same. This level corresponds with the zero mark on the scale, when the apparatus is placed on a horizontal base.

After the apparatus is set up or previously thereto, the tank 10 is charged with air under pressure, the valves 21^a and 24 being first closed. After a sufficient charge of air has been placed in the tank, the tourniquet 120 is adjusted in the usual manner and the valve 21^a opened. This permits the air under pressure to escape through the tube 21 whence it passes into the transverse passage 20 and the vertical passage 18^a in the cap of 125 130

the mercury chamber and through the tube 22 to the tourniquet. The air is permitted to freely enter through the tube 21 until the pulse disappears in the usual manner, 5 whereupon the valve 21^a is closed, thus cutting off the supply of air from the storage tank. In case the pressure upon the return of the pulse is desired to be noted, the valve 24 is slightly opened thus permitting the 10 gradual escape of the air in the mercury chamber and in the tourniquet until the pulse is first detected when the valve 24 is closed and the pressure noted.

The measuring of the blood pressure is a 15 rather delicate operation and where a pump is used to provide the increasing pressure, which pump must be operated by one hand while the determination is being made, the pressure increase is not gradual or even, so 20 that the mercury rises in the tube in spurts or jumps and it is difficult to get an accurate reading indicating the level of the mercury at the instant the pressure is sufficient to produce a cessation of the pulse and two or 25 more operations may be required before a satisfactory reading is made. The operation is impeded also by the fact that one hand of the operator is used in determining the pulse while the other hand is required to operate the pump.

With the use of my improved apparatus not only is the manipulation of the pump dispensed with so that the operator has the 30 free use of the hand heretofore required for 35 operating the pump, but in addition, the pressure is steady and under accurate control so that the rise of the mercury in the tube is gradual and uniform and its height, the instant the pulse stops, may be accurately determined.

My improved sphygmometer may be conveniently carried in a box made, in the case of the embodiment of my invention illustrated in the drawings, of a width and length 40 to receive the base, and of a depth sufficient to receive the mercury cup of the manometer, since, in the case referred to, all of the parts of the apparatus, when the mercury tube of the manometer is turned down 45 alongside of the storage tank, are confined within such limits as to be readily packed in such a case or box.

While in describing one embodiment of my invention I have referred to certain details of mechanical construction and arrangement, it is to be understood that my invention is not limited in any way except 50 as pointed out in the appended claims.

I claim as my invention—

1. A sphygmometer comprising a base, a 60 storage tank rigidly secured to said base and adapted for the storage of fluid under pressure, a fluid pump supported within said tank and operable from the outside of said tank, a manometer rigidly supported on said 65 base, means providing a conduit leading from said tank to said manometer, a valve located in said conduit adapted for the control of the flow of fluid therethrough, a fluid controlled tourniquet and means for 70 connecting said manometer with said tourniquet.

2. A sphygmometer comprising in combination, an elongated storage tank adapted for containing fluid under pressure, a manometer rigidly connected to one end of said tank, said manometer comprising a mercury chamber and a tube open at its upper end and connected at its lower end to the bottom of said mercury chamber, means rotatively connecting said mercury tube to said mercury cup affording swinging movement of said tube about its lower end to bring it into a position parallel to the length of said tank and adjacent thereto, means providing 80 a conduit between said storage tank and said mercury chamber, a valve located therein adapted to control the flow of fluid therethrough, a fluid controlled tourniquet and means for connecting said manometer with 85 said tourniquet.

3. A sphygmometer comprising in combination, a manometer and means for applying fluid pressure thereto, said manometer embracing a cup having a base and containing a chamber located above said base, said base being provided with a passage leading from the bottom of said chamber and through a lateral opening in said base, a plug secured in said lateral opening of the 90 base, said plug having a passage connected with said passage in the base and opening laterally through said plug, a mercury tube open at the top, and means supporting said 95 mercury tube, said means being rotatively mounted on said plug and containing a passage opening into said tube and adapted to register with the passage in said plug.

In testimony that I claim the foregoing as my invention I affix my signature in the 100 presence of two witnesses, this 15th day of December A. D. 1911.

WILLIAM E. HASELTINE.
